UNITED STATES PATENT OFFICE.

ALFRED RICHARD GEORG VOGT, OF CHEMNITZ, GERMANY, ASSIGNOR TO THE FIRM: WANDERER WERKE-VORM. WINKLHOFER & JAENICKE A. G., OF SCHONAU, NEAR CHEMNITZ, GERMANY.

TYPEWRITER.

Application filed September 16, 1921. Serial No. 501,153.

To all whom it may concern:

Be it known that I, ALFRED RICHARD GEORG VOGT, a citizen of the German Republic, and a resident of Chemnitz, Saxony, 5 Germany, have invented certain new and useful Improvements in Typewriters, of which the following is a specification.

This invention relates to a case-shift device for typewriting machines of the kind 10 where means for multi-case-shift, for instance double case-shift, are provided and in which the platen may be lifted or lowered for equal lengths of way from its central or normal position which is at the same time 15 its position of rest, and may be locked in the middle positions.

It is already known to effect such reversals by means of bell-crank levers, knee-joints, curved guides, or the like, but all these means 20 have more or less the drawback that they must be very exactly manufactured. But even then a certain play in the link connections, bearing places, etc., is unavoidable, becomes perceptible by its detrimental effects 25 especially after longer use, and can be obviated either but very difficultly or not at all. This play entails an excess of motion of the platen in its middle position whereby the written line becomes bent.

30 The object of the present invention is to obviate these drawbacks, and the means for this purpose consist in a combination and arrangement of parts, the chief features of which are the following: The platen is supported in a platen frame which, in its turn, 35 is supported upon a shiftable supporting frame; case-shift levers control the shifting of said latter frame; the supporting frame has two case-shift positions, being movable 40 from a central or normal position to an upper or to a lower one. The system of levers employed in the novel mechanism is connected with the shiftable parts only during the lifting and the lowering, whereas when 45 the central or normal position has been reached the platen abuts against and is securely held by locking levers, which have been positively moved into the respective position, it being now unnecessary to pay 50 any regard to the play that may exist in the bearings and places of connection of that system of levers. It is, thus, unnecessary to be particularly careful in manufacturing the various parts, because solely the locking

levers ensure the central or normal position 55 of the platen. Angular adjusting members allow a convenient and suitable adjustment and re-adjustment of the platen as regards its central or normal position.

The locking levers which are provided 60 with oblique slots are positively guided by the transmission of motion of the case-shift key-levers, whereby the case-shift frame is either released or locked in a reliable manner and at the proper time. There are no 65 other springs than those requisite for moving the case-shift key levers back into their former position, which entails, besides a favorable key lever ratio, a smooth working of the mechanism, as well as a small expenditure of power for operating it.

In order to make my invention more clear, I refer to the accompanying drawings, in which similar letters denote similar parts throughout the several views, and in which 75 Fig. 1 is a side view of the mechanism, the platen being in its middle position; Fig. 2 is a plan of the parts shown in Fig. 1, the platen and its frame being, however, left away; Fig. 3 is a detail of the lower part 80 of the righthand side of Fig. 1; Fig. 4 is a front view of the lefthand end of the parts illustrated in the middle part of the righthand side of Fig. 1; Fig. 5 is an illustration similar to Fig. 1 showing the position of the 85 parts after the platen has been lifted; and Fig. 6 is a similar illustration showing the position of the parts after the platen has been lowered.

The platen 1 is supported in a known manner in a frame 2 which may be lifted and lowered together with said platen and all other parts connected with it. The part 90 of the frame 2 below the platen 1 consists of a rod 3 supported by a roll 5 carried by the case-shift frame 4 which is movably connected at its lower end by links 7 with an axle 7' held between screws 8 passing through projections 6' of the frame 6. The links 7 and the case-shift frame 4 are connected with each other by screws 9.

The case-shift key levers 10 and 11 (Figs. 1, 2, 5, and 6) are attached to the machine frame by screws 12 and held in their proper elevated position by springs 14 affixed at 105 their upper ends to the levers 10 and 11 and at their lower ends to pins 13 screwed into the frame. The lever 10 has at its rear arm

10^a a hole receiving a pin or pivot 16 secured to a link or push member 15 (Figs. 1, 4, 5) provided with an angular slot 15^a through which extends a screw 17 screwed into the 5 frame of the machine. Owing to the slot 15^a being angular, the link or member 15 performs a swinging motion if it is lifted or lowered by the case-shift key lever 10, 10^a. A screw 18 also screwed into the machine 10 frame supports a double-armed locking lever 19, the lower arm of which has a slot 19^a and is coupled with the member 15 by a pin 20 affixed to the upper end of this member and extending through said slot 19^a. 15 Owing to this connection, the locking lever 19 may be oscillated by the push member 15. The upper end of the lever 19 forms a nose 19^b which may engage an angular locking member 21 (Fig. 1) connected with the 20 case-shift frame by an adjusting screw 22 and a fixing screw 23.

The case shift lever 11 which serves for lowering the platen is connected at its rear end with a lever 25 attached to the frame 25 by a screw 26 and connected in its turn by a pin 16 with a link or member 27 having an angular slot 27^a and being supported by a screw 17. This is practically a similar combination and arrangement of parts as 30 shown in the lower part of the right hand side of Fig. 5 (link or member 15, slot 15^a, screw 17). The member 27 is coupled with a locking lever 24 by means of a pin 20 affixed to it, and by a slot 24^a provided in 35 the lever 24. This latter is attached to the frame by the screw 18. The upper end of the lever 24 forms a nose 24^b which cooperates with an angular adjusting member 21 affixed to the case-shift frame by an 40 adjusting screw 22 and a fixing screw 23. In the position of rest of the platen the nose 24^b engages the member 21 from below and prevents the platen, or the platen frame 2 respectively from sinking.

45 The manner of operation of the device is as follows:

If the case-shift lever 10 is depressed (Fig. 5), its short arm 10^a swings upwards and lifts the push member 15 which, owing to 50 the shape of its guide-slot 15^a, gets into the path of the case-shift frame 4 and below this latter in order to lift it when the key is further depressed. During that motion of the member 15 the locking lever 19 has 55 been turned to the left (Fig. 5) because the pin 20 of said member has moved into the upper part of the slot 19^a, whereby the nose 19^b has been drawn off the angular member 21. The case-shift frame 4 is now free to 60 be moved upwards until it contacts with an abutment provided for the purpose.

When the pressure is removed from the 65 key of the case-shift lever 10, the spring 14 moves the whole system of levers back into its former position, whereas the shiftable

parts are moved into a medium position by means of a spring not shown in the drawing. The locking lever 24 which is connected with the case-shift key lever 11 has not changed its position during the just-mentioned movement of the other parts and stops the returning case-shift frame when arriving in its middle position. After said frame has arrived in this position, the locking lever swings back into its locking position, where-as the push member 15 swings to the left, i. e., away from the path of the case-shift frame and, thus, from this frame itself.

In order to shift the platen downwards into its deepest position, the case-shift key 80 11 is depressed (Figs. 1 and 6). By this movement the pull member 27 is drawn downwards by the mediation of the intermediate lever 25, and owing to the angularity of the slot 27^a of said member 27 85 through which the pin 17 passes, the said member is swung to the right and its hook-shaped upper end engages an aperture of the case-shift frame 4 so as to draw this frame further down when the key 11 is 90 further depressed. The angular motion of the pull member 27 is transmitted by its pin 20 and the angular slot 24^a of the locking lever 24 to this lever, the nose 24^b of which swings to the left, that is to say: away from the path of case-shift frame. This latter, together with the platen, may now glide down until it contacts with an abutment provided for that purpose but not shown in the drawing.

When letting loose the key 11, all the parts actuated in the before-described manner are returned into their middle position, partly under the effect of the spring 14, partly under the effect of another spring acting 105 upon the case-shift frame 4, but also not shown in the drawing. The parts are then stopped in their middle position by the nose 19^b of the first locking lever 19, the position of which had not been changed. The nose 24^b of the locking lever 24 engages, finally, again the angular member 21 whereby the platen is again locked in its middle position.

The device is arranged upon both sides of the typewriting machine and the motion is 115 transmitted from the one side to the other by the levers 28 which are firmly connected with a hollow shaft 30 carried by an axle 29. The levers 28 have slots 31 engaged by pins 32 (Fig. 2), firmly connected with the 120 case-shift key levers 10 and 11.

Having now described my invention, what I claim as new and desire to secure by Letters Patent of the United States is:

1. A case-shift device for the platen of 125 typewriting machines having means for multi-case-shift, comprising in combination: a platen; a platen-frame; a shiftable frame supporting said platen frame and having two case-shift positions and being adapted 130

to be moved from a central or normal position to an upper or to a lower one; two double-armed locking levers arranged at the machine frame and being adapted to lock 5 said platen frame in its middle position against upward and downward position; an angular slot in the lower arm of each of said levers; two double-armed case-shift key levers; an upwardly directed push member 10 hinged to the rear arm of one of said levers; an upwardly directed pull member hinged to the rear arm of the other of said levers; an angular slot in each of said members; a stationary guide member for each of these 15 slcts; and a pin provided in the pull member and in the push member and extending through the associate slot of the associate locking lever, for the purpose set forth.

2. A case-shift device for the platen of type- 20 writing machines having means for multi-reversal, comprising in combination: a platen; a platen-frame; a shiftable frame supporting said platen frame and having two case-shift positions and being adapted 25 to be moved from a central or normal position to an upper or to a lower one; two double-armed locking levers arranged at the machine frame and being adapted to lock said platen frame in its middle position

against upward and downward position; an 30 angular slot in the lower arm of each of said levers; two double-armed case-shift key levers; pivots for said locking levers, said pivots being located immediately in front of said case-shift frame; an upwardly directed 35 push member hinged to the rear arm of one of said levers; an upwardly directed pull member hinged to the rear arm of the other of said levers; an angular slot in each of said members; a stationary guide member for 40 each of these slots; and a pin provided in the pull member and in the push member and extending through the associate slot of the associate locking lever; said push member and pull member being out of engagement 45 with the said case-shift frame in middle position of the same and the said locking levers taking up the pressure and the pull of the case-shift frame vertically with respect to the centre of their pivots, substantially as shown and described.

In witness whereof I have hereunto set my hand in presence of two witnesses.

ALFRED RICHARD GEORG VOGT.
